DRIVE TRANSMISSION

Marcus A. Holpfer, Coraopolis, Pa.

Application June 6, 1939, Serial No. 277,642

2 Claims. (Cl. 192—59)

This invention relates to a fluid controlled device transmission primarily designed and intended for use in connection with the forward drive mechanism of a motor vehicle, but it is 5 obvious that the device may be employed in any other type of apparatus or for any other purposes wherein it is found to be applicable.

Important objects and advantages of the invention are to provide a drive transmission of 10 the character described, which is hydraulically controlled, which does not require a separate clutch structure to effect its successful operation, which is quietly, positively and automatically operable for transmitting change-speed driving power, which is simple in its construction 15 and arrangement, compact, and comparatively economical in its manufacture, installation, operation and maintenance.

With the foregoing and other objects in view 20 which will appear as the description proceeds, the invention resides in the novel construction, combination and arrangement of parts herein specifically described and illustrated in the accompanying drawing, but it is to be understood 25 that the latter is merely illustrative of an embodiment of the invention, and that the actual needs of practice and manufacture may require certain mechanical variations from the embodiment shown. It is, therefore, not intended to 30 limit the invention to the disclosure thereof herein illustrated, but rather to define such limitations to the scope of the claims hereunto appended.

In the drawing wherein like numerals of reference designate corresponding parts throughout the several views:

Figure 1 is a longitudinal cross section view of 35 a drive transmission constructed in accordance with the invention.

Figure 2 is a front end view of the casing structure with the front end plate removed from the latter.

Figure 3 is a transverse sectional view on line 3—3, Figure 1.

Figure 4 is a transverse cross sectional view of one of the plungers embodied in the present invention.

Referring in detail to the drawing 1 denotes an elongated, cylindrical casing including a rear end plate 2 secured thereto by bolts 3, and a front end plate 4 secured thereto by bolts 5. The interior of the casing is formed with a thick, transversely extending wall 6, which latter provides a plunger chamber 7 disposed forwardly thereof, a fluid supply chamber 8 dis-

posed rearwardly thereof, and a compression chamber 9 disposed in said wall at the rear end thereof.

The casing wall 6 is formed to provide a plurality of cylinders 10. The latter are disposed longitudinally in parallel relation to each other, and the front ends thereof open into the plunger chamber 7. A plunger 11 is shiftably mounted for longitudinal, reciprocal movement in each of the cylinders. The length of the plungers is greater than the depth of the cylinders, whereby even when said plungers are in the furthermost rearward discharging positions, the forward end portions thereof will project into the plunger chamber.

A driven shaft 12 is formed integral with or otherwise suitably secured to the rear end plate 2, and a driving shaft 13 operated by an internal combustion engine or other apparatus providing the prime source of power, extends into the casing, and is suitably journaled for rotation in the front end plate 4 by a suitable stuffing box and packing gland 14, and in forward end of the casing wall 6, as indicated at 15. The shafts 12 and 13 are longitudinally aligned relatively to each other and have a common axis with the axis of the cylindrical casing.

The driving shaft 13 is formed with an enlarged cylindrical portion 16, which may be formed integral with the former or fixed thereto in any suitable manner. The shaft portion 16 is disposed within the plunger chamber 7, of the casing, and is preferably commensurate to the length of said plunger chamber. An outwardly projecting annular cam 17 surrounds and is formed integral with the periphery of the shaft portion 16. The cam engages in suitable transversely extending grooves 18, which latter are formed on the inner sides of the projecting forward end portions of respective plungers 11 within the plunger chamber 7. It will be apparent that the rotation of the annular cam 17 will impart longitudinal, reciprocal movement to all of the engaged plungers in respective cylinders 10.

The operation of the drive transmission involves the use of liquid in the form of oil or any other suitable fluid. The plunger chamber 7, the supply chamber 8, and the compression chamber 9 are completely filled with the operating fluid, and the latter may be placed in the casing or drained therefrom through a plugged aperture 19 suitably located in the casing.

The plunger chamber 7 and the supply chamber 8 are communicably joined by passages 20

extending through the casing wall 6. The rear closed end of each of the cylinders 11 communicates with the supply chamber 8 by a passage controlled by a comparatively large capacity intake valve element 21, and with the compression chamber 9 by a passage controlled by a relatively small exhaust valve element 22. The valve elements 21 and 22 are preferably spring controlled ball type, of the usual construction, and function automatically for the purposes employed.

As clearly illustrated in Figure 1, the forward or suction stroke of each of the plungers will open the intake valve element 21 to allow the entrance of the operating fluid from the supply chamber 8 to the cylinder 10, while the associated exhaust valve element 22 will be held in the closed position preventing the entrance of the fluid from the cylinder to the compression chamber 9.

The rearward or discharge stroke of each of the plungers 11 will close the intake valve element 21 to prevent entrance of the fluid from the cylinder to the supply chamber 8, while the associated discharge valve element 22 will be opened to allow the passage of the fluid from the cylinder to the compression chamber 9. Thus, it will be evident that at each reciprocal stroke of the plungers, the operating fluid will be drawn from the supply compartment 8 and discharged into the compression chamber 9.

An elongated needle valve 23 is mounted and longitudinally shiftable in the driving shaft 13 and projects rearwardly from the rear end of the latter into the compression chamber 9. The shiftable movement of the needle valve 23 is limited by a cross pin 24, which latter is fixed adjacent to the front end of said needle valve and engaged in a pair of opposed slots 25 formed in driving shaft 13. The ends of the cross pin are fixed in a slide collar 26 longitudinally shiftable on the driving shaft but revolvable with the latter.

A seating plug 28 is threadedly secured to the rear side of the casing wall 6 and provides the rear wall for the compression chamber 9. The plug 28 has a centrally disposed seating passage 29 providing communication between the compression chamber 9 and the supply chamber 8. The rear free end of the needle valve 23 is tapered and adapted for seating in said passage 29 for opening or closing the latter during the operation of the device in the manner and for the purposes to be described.

A piston 30 is mounted in a cylinder 31 formed in the rear end plate 2 and carries a fixed forwardly projecting push rod 32. The latter and said piston 30 extend into the supply chamber 8 and are longitudinally aligned with the needle valve 23, and the free end of said push rod extends into the passage 29 and is always seated against the free tapered end of the needle valve, as shown in Figure 1. A spiral spring 33 is mounted in a pocket provided therefor in the driven shaft 12 and normally functions to force the piston 30 forwardly in the cylinder 31 to maintain the engagement of the push rod 32 against the needle valve 23.

When the piston 30 is in its furthermost rearward position in the cylinder 31, the forward end thereof projects from the open forward end of the latter and projects into the supply chamber 7. A transversely extending cross passage 34 is formed in said projecting end of the piston and communicates with the through passage in the 75 piston, which latter passage is controlled by an

intake valve element 35 of the spring controlled ball type. During the forward movement of the piston 30 in the cylinder 31, the valve element 35 opens to allow the operating fluid to enter said cylinder through the piston, but the rearward movement of the piston into its cylinder closes the valve element 35 and slowly forces the fluid from the cylinder through a relatively small passage 36 in the piston into the cross passage 34 and through the latter into the supply chamber 8. The purpose of forcing the fluid through the small passage 36 is to retard the return movement of the piston 30 from its fully projected position in the cylinder 31 during the operation of the device in the manner to be described.

The needle valve 23 is regulated and controlled by the operation of a governor attachment comprising a plurality of suitable centrifugally actuated weights 37. Each of the latter is pivotally connected and carried by a suitable support 38 fixedly secured to the front end plate 4.

The weights 37 are engaged in an annular groove 39, formed in the slide collar 26, in a manner, when extended, to shift the latter on the driving shaft 13 toward the casing to thereby force the needle valve 23, connected to said slide collar by the cross pin 24, to the closed position by the engagement of the tapered free end thereof in the seating passage 29.

A spiral spring 39 is mounted on the driving shaft 13 with one end abutting against the rear face of the slide collar 26, and with the other end thereof abutting against an adjusting ring 40. The latter surrounds the driving shaft, and is threadedly engaged in the packing gland 14. The ring 40 is adjustable to adjust the tension of the spring 39, and the latter normally functions to shift the slide collar 26 forwardly on the driving shaft to shift and normally maintain the needle valve 23 in the open position from its engagement in the seating passage 29.

To shift the needle valve 23 to the open or inoperative position against the centrifugal action of the weights 37 while the latter are operating to close said needle valve in the manner set forth, a manually operated control mechanism is provided. The latter comprises a pedal 41, which is suitably supported and pivoted to the equipped vehicle structure 42.

The pedal is further pivotally connected to a slotted slide bar 43 longitudinally slidable in the vehicle structure and carrying a pair of spaced depending lugs 44, which engage the peripheral edge margin of an annular flange 45 formed integral with the slide collar 36. A hand operated lever 46, pivotally connected with the slotted slide bar and with the vehicle structure, is likewise operable for shifting the needle valve to the open position. The lever 46 is associated with a spring controlled latch 48 and a notched quadrant 49 for securing when necessary, the needle valve in the open, inoperative position during the operation or rotation of the driving shaft 13.

A spring 50, connecting with the vehicle structure 42 and with the slide bar 45, normally functions to return and hold the latter in the inoperative position, as shown in Figure 1. Unless the lever 46 is secured in the inoperative position, the construction, arrangement, and operation of the slotted slide bar and of associated parts, allow the operation of the pedal 41 independently of the lever 46, or the operation of the latter independently of the pedal or the automatic control of the needle valve 23 by the operation of

the centrifugally actuated weights 37 independently of either the pedal or the released lever.

In practice the operation of the improved fluid controlled drive transmission is as follows:—Assuming the apparatus employed for driving a motor vehicle equipped therewith, the operator sets the lever 46 in the released position, which latter is shown in Figure 1. As the spring 39 normally holds the slide collar 26 in the forward position 10 the needle valve 23 is thereby held in the open position, being disengaged from the seating passage 29.

At idling speed of the vehicle engine, the governor weights 37 will not be actuated to extend 15 the latter sufficiently to shift the needle valve 23 to the closed position, and while the engine or driving shaft 13 is rotating at such idling speed the driven shaft 12 will not be revolved, as the plungers 11 will be operating to simply circulate 20 the fluid from the supply chamber 8 through the compression chamber 9 back into the supply chamber.

When the driving shaft 13 is rotating at idling speeds, the liquid flow, occasioned by the reciprocation of the pistons 11 by the cam 17 on the driving shaft 13, will not be sufficiently resisted to impart any rotation to the casing 1. As the speed of the driving shaft 13 is increased a resistance to liquid flow, due to restricted size of the 30 passages to the chamber 9, will obtain, thereby causing initial rotation of the casing 1. As casing 1 picks up in speed the weights 37, under the influence of centrifugal force, will be actuated to move the needle valve 23 toward its closed position 35 against the action of the spring 39 and the operation of the piston 30, thereby tending to cause the casing 1 with the driven shaft 12 to rotate with the driving shaft 13.

During the protracted movement of the needle valve 23 to the closed position the driving shaft 13 is permitted to rotate at a greater speed than the casing and driven shaft 12 due to the forced discharging fluid escaping from the compression chamber 9 through the seating passage 29. The 40 tendency of the casing and driven shaft to rotate during the retarded movement of the needle valve will gradually increase until the driving force of the driving shaft is sufficient to actually impart reduced speed rotation to the entire casing and the driven shaft, and thus provide the initial starting impetus and subsequent starting propulsion of the driven shaft.

After the needle valve 23 has been shifted to the fully closed position, the fluid can no longer escape through the seating passage 29, and in consequence the casing and the driven shaft 12 will rotate with the driving shaft 13 and establish the direct driving connection between the latter and the driven shaft.

If the driven shaft 12 is overloaded for the direct operation of the driving shaft 13, the reduced speed thereof will cause the contraction of the governor weight 37 by the action of the spring 39, and thereby automatically shift the needle valve 60 to the open position, when again the varied speeds of respective shafts will be effected to drive the driven shaft at the necessary low and intermediate speeds required to again establish the direct drive of the driving and driven shafts.

While my improved transmission will function to rotate in either direction, the transmission does not provide for the separate reverse rotation of the driven shaft 12, as such reverse mechanism forms no essential part of the present 70 disclosure, but it is evident that some suitable re-

verse mechanism may be successfully embodied in the improved transmission without departing from the principle of the invention.

The present invention provides a most durable and efficient device of its kind, which is entirely 5 automatic in its operation, and which may be successfully employed to operate a shaft at any speed to provide the power necessary to effect the start, propulsion, or operation of the apparatus it is intended to operate.

10

What I claim is:

1. In a fluid controlled drive transmission for a power apparatus, the combination of a casing formed with a transversely extending wall providing a fluid supply chamber, a plunger chamber and a fluid compression chamber, a plurality of longitudinally disposed cylinders formed in said wall and opening into said plunger chamber, a plunger mounted in each of said cylinders and projecting into said plunger chamber, a driven shaft fixed to said casing, a driving shaft 15 revolvably engaged in said casing and being aligned with said driven shaft, a valve element mounted and longitudinally shiftable in said driving shaft, an annular cam carried by and surrounding said driving shaft and engaging in grooves at the inner sides of said plungers for imparting reciprocal movement to the latter for drawing the fluid from said supply chamber and for forcing the fluid into the compression chamber, and centrifugally actuated means carried by said casing operable for shifting said valve element for controlling the passage of the fluid from said compression chamber to said supply chamber to confine 20 the fluid in said compression chamber and thereby causing the rotation of said casing and of said driven shaft with said driving shaft.

2. A fluid controlled drive transmission comprising an elongated cylindrical casing including a front end plate and a rear end plate, a transversely disposed wall formed integral with said casing and providing the interior of the latter with a fluid supply chamber, a plunger chamber and a fluid compression chamber, a driven shaft 40 fixed to said rear end plates, a driving shaft journaled for rotation in said front end plate and in said wall, a plurality of longitudinally extending cylinders formed in said wall and opening into said plunger chamber, a plunger mounted for reciprocal movement in each of said cylinders 45 and projecting into said plunger chamber, a transversely extending groove formed in the inner side of the projecting end of each of said plungers, a comparatively large capacity intake valve element automatically operable for controlling the entrance of the fluid from said supply chamber to respective cylinders, a comparatively small capacity discharge valve element for automatically controlling the discharge of fluid 50 from respective cylinders to said compression chamber, the rear wall of said compression chamber being provided with a seating passage, a needle valve mounted and longitudinally shiftable in said driving shaft and projecting into said compression chamber and being shiftable to open 55 or close said seating passage, an annular cam fixed to and extending around said driving shaft, said cam engaging in said grooves and being operable for imparting longitudinal reciprocal movement to said plungers for drawing the fluid from 60 said supply chamber through said intake valve elements to said cylinders and for discharging fluid from said cylinder through said discharge valve elements, a slide collar mounted and longitudinally shiftable on said shaft and being con- 65

70

75

nected with said needle valve, resilient means mounted on said driving shaft and engaging said collar for shifting said needle valve to the open position, centrifugally actuated means carried by said casing and engaging said collar automatically operable for shifting said needle valve to the

closed position, means for retarding the movement of said needle valve to the closed position, and manually operated means for shifting the needle valve to the open position and for securing the latter in the open position.

MARCUS A. HOLPFER.
